(57) **CLAIM**

An ornamental design for a switching valve, as shown and described.

DESCRIPTION

FIG. 1 is a side elevational view of a second embodiment of a switching valve showing my new design;

FIG. 2 is a view similar to FIG. 1 rotated 180 degrees;

FIG. 3 is a view similar to FIG. 1 rotated 270 degrees;

FIG. 4 is a view similar to FIG. 1 rotated 90 degrees;

FIG. 5 is a top plan view thereof; and,

FIG. 6 is a bottom plan view thereof.

The broken lines shown in FIGS. 1 and 2 are for illustrative purposes only and form no part of the claimed design.
